UNITED STATES PATENT OFFICE.

CHARLES A. TATUM, OF NEW YORK, N. Y., ASSIGNOR TO WHITALL TATUM COMPANY, OF NEW YORK, N. Y., A CORPORATION OF NEW JERSEY.

BREAST-PUMP.

1,101,973.

Specification of Letters Patent. Patented June 30, 1914.

Application filed April 5, 1910. Serial No. 553,631.

To all whom it may concern:

Be it known that I, CHARLES A. TATUM, a citizen of the United States, residing at New York city, in the county of New York and State of New York, have invented new and useful Improvements in Breast-Pumps, of which the following is a specification.

My invention relates to a new and improved form of breast pump consisting of a glass receptacle of any desired form and a rubber bulb attached thereto, the principal improvement being in the means of attaching the bulb to the glass receptacle.

In the accompanying drawings Figure 1 is a sectional view of the receptacle and bulb with the bulb partially broken away. Fig. 2 is a sectional view taken on the line α α of Fig. 1 looking toward the bulb. Fig. 3 is a modification showing a portion of the neck of the receptacle and the bulb partly broken away. Fig. 4 is a sectional view of an alternate construction.

The device consists of a glass receptacle a which may be of the form shown in the drawing or any desired form having a mouth or opening b . The neck of the glass receptacle is shown opposite the mouth b and is indicated by c , or the mouth may be on the side of the receptacle if desired. The outside of the neck c is threaded as shown at d . The bulb f is made with a corresponding thread e . The rubber bulb f is secured to the receptacle by screwing the rubber bulb f on to the glass receptacle a and to make a perfectly tight closure and secure fastening, a rigid collar g preferably of metal, fits over the neck of the bulb f and renders a secure and tight fastening and at the same time allows the bulb to be easily removed for cleansing purposes.

In the alternate form of construction shown in Fig. 4 the rigid collar g is firmly

secured by vulcanization or any other desired manner to the inside of the neck of the bulb f and the receptacle a has a screw thread d formed on the inside and the rubber bulb f has a corresponding thread to fit into it.

The advantages of my construction are that the bulb f can be quickly and firmly and at the same time rigidly secured to the glass receptacle a and also easily removed for cleansing purposes.

I claim:

1. A breast pump comprising a glass receptacle provided with an inlet mouth and a tubular stem having exteriorly rounded screw threads located opposite to the mouth; in combination with an elastic bulb provided with a neck having internal rounded threads formed in the elastic for engagement with the threads formed on the stem of the receptacle, and a metallic detachable band encircling practically the width of the neck adapted to compress the rubber when the bulb is screwed on to the stem. 55

2. A breast pump comprising a glass receptacle provided with an inlet mouth and a tubular stem having exterior screw threads located opposite to the mouth, in combination with an elastic bulb provided with a neck having internal threads formed in the elastic for engagement with the threads formed on the stem of the receptacle, and a metallic detachable band encircling the neck 70 adapted to press the rubber when the bulb is screwed onto the stem. 75

In testimony whereof I have hereunto set my hand in the presence of two subscribing witnesses.

CHARLES A. TATUM.
